UNITED STATES PATENT OFFICE

154,292

DESIGN FOR A SPOON OR OTHER ARTICLE
OF FLATWARE

Abraham Litvin, New Haven, Conn.

Application June 9, 1948, Serial No. 146,841

Term of patent 3½ years

(Cl. D54—12)

To all whom it may concern:

Be it known that I, Abraham Litvin, a citizen of the United States residing at New Haven, in the county of New Haven and State of Connecticut, have invented a new, original, and ornamental Design for a Spoon or Other Article of Flatware, of which the following is a specification, reference being had to the accompanying drawing, forming part thereof.

Fig. 1 is a face view of a spoon or other article of flatware showing my new design;

Fig. 2 is a transverse sectional view taken on the line 2—2 of Fig. 1; and

Fig. 3 is a similar sectional view but taken on the line 3—3 of Fig. 1.

The essential features of my design for a spoon reside in the parts shown in full lines.

I claim:

The ornamental design for a spoon or other article of flatware, substantially as shown and described.

ABRAHAM LITVIN.
